G. Wood,

Clamp.

No. 100,700.

Patented Mar. 8, 1870.

United States Patent Office.

GEORGE WOOD, OF PHILADELPHIA, PENNSYLVANIA.

Letters Patent No. 100,700, dated March 8, 1870.

IMPROVEMENT IN FLOOR-CLAMP.

The Schedule referred to in these Letters Patent and making part of the same

I, GEORGE WOOD, of the city of Philadelphia, and State of Pennsylvania, have invented certain new and useful Improvements in Floor-Clamps, of which the following is a specification.

My invention mainly consists of a peculiar combination and arrangement of the retaining and forcing devices of the apparatus, by means of bevel-gearing connecting the said parts, and a partially rotating gripping-cam, and certain auxiliary parts in connection with the former; in such a manner that when the apparatus is placed on a joist or other timber for forcing the flooring-boards or other pieces together, the rotation of said gearing in one direction by means of a crank or otherwise, fixes the retaining device upon the joist, and clamps the boards at one operation; and after which a reverse movement of the crank releases the forcing and retaining device at the same time, whereby much time is saved over other other floor-clamps, which have first to be secured to the joist before the operation of clamping is commenced, and when the latter is finished the forcing device has to be released before the clamp can be loosened from the joist.

To enable others skilled in the art to make and use my invention, I will now give a detailed description thereof.

In the accompanying drawings which make a part of this specification—

Figure 1 is a plan or top view of the improved clamp.

Figure 2 is a side elevation of the same.

Figure 3 is a plan of the bed-plate A.

Figure 4 is a side elevation of the same.

Figure 5 is an isometrical view of the forcing-clamp in a reversed position.

Like letters in all the figures indicate the same parts.

A is a bed-plate, to which the several parts of the device are attached.

The horizontal plate a rests upon the joist, and the gripping ribbed jaw b is forced against one side of the same, as hereinafter described.

The said bed-plate is shown in detail in figs. 3 and 4. B is the forcing-clamp, and

C the driving-screw, which works in the rear end of the straight part d, which has a nut cut in its rear end, to receive the screw C, the other part being hollowed out to form a shield for the same.

D is a partially-revolving gripping-cam, on the vertical short shaft E, which has an arm, f, on its upper end, which is provided with a pulling-catch, F.

On the driving-screw C there is a bevel-pinion, G, which gears into the wheel H, the cam D being in the position represented in dotted lines in fig. 1, so as to admit of the apparatus being placed on the joist I, with the forcing-clamp B against the board g. The wheel H is turned in the direction of the arrow, so as

to rotate the driving-screw C, bringing the clamp B sufficiently tight against the board to cause the partial receding of the bed-plate A, whereby the cam D is forced partly around, and the joist is clasped tight between it and the jaw b. The screw C being still revolved until the board g is clamped tight against the board g', the part d of the clamp sliding in the groove h on the upper side of the bed-plate A, and in the socket i on the front end of the same.

To facilitate the gripping-ribs c of the jaw b, and the ribs or teeth of the cam D taking hold of the joist, by having their direction inclined to that of the grain of the wood, and also to prevent the front end of the bed-plate A rising during the clamping operation, the said teeth are arranged in angular position, as represented in the drawings.

When the apparatus has to be removed for clamping another board, the motion of the driving-screw C of the gearing is reversed, and the shoulder h of the catch F coming against the shoulder k of the groove l, into which the end of the catch had been previously forced by the spring J, which is attached to the arm f, causes the incline m of the catch to bear against the stationary incline n on the bed-plate A, whereby the arm f is pulled around until the cam D is freed from the joist for the removal of the apparatus.

There is a spring, K, attached to the bed-plate A, against which the pin o, which projects from the under side of the arm f, bears in its backward position, which spring forces the arm back into its first position.

The improved clamp may be advantageously used for the clamping of doors, sash, and for many other things, and it may be used as a lifting-jack by placing it endwise on the floor or other support, when the catch is released from the incline n, causing the cam to engage with the joist.

What I claim as new, and desire to secure by Letters Patent, is—

1. The combination of the catch F; spring J, arm f, cam D, forcing-clamp B, and bed-plate A, constructed and operating as described, and for the purpose specified.

2. The clamp herein described, consisting of the bed-plate A, forcing-clamp B, cam D, catch F, and their operating mechanism, constructed and arranged to operate as set forth.

In testimony that the above is my invention, I have hereunto set my hand and affixed my seal this 6th day of December, 1869.

GEORGE WOOD. [L. S.]
